UNITED STATES PATENT OFFICE

JOSEPH A. MILLER, OF HOPEDALE, MASSACHUSETTS, ASSIGNOR TO DRAPER CORPORATION, OF HOPEDALE, MASSACHUSETTS, A CORPORATION OF MAINE

SPINDLE BEARING

Application filed May 25, 1927. Serial No. 194,202.

This invention relates to improvements in self-adjusting spindle bearing constructions and one of the objects thereof is to provide a spindle bearing of relatively simple construction which will avoid the pumping of oil over the top of the bolster casing.

A further object of the invention is to provide a bolster with a relatively narrow upper bearing so located with respect to the length 10 of the bolster that the oil within the bolster casing will exert a cushioning effect upon the bolster both above and below the bearing and without the likelihood of splashing oil over the top of the bolster casing.

15 A further object of the invention is to provide a device of this character in which the upper bearing is provided with recesses to permit the free circulation of the oil within the bolster casing while greatly reducing or 20 avoiding the pumping action of the vibrating bolster.

Other objects and features of the invention will more fully appear from the following description and the accompanying drawings 25 and will be particularly pointed out in the claims.

In the drawings:

Fig. 1 is a view, mainly in vertical section, of a bolster casing and bolster embodying the 30 present invention with the spindle mounted in the bolster;

Fig. 2 is a detail transverse sectional view on line 2—2 Fig. 1;

Fig. 3 is a detail transverse sectional view 35 on line 3—3 Fig. 1;

Fig. 4 is a detail transverse sectional view on line 4—4 Fig. 1; and,

Fig. 5 is a detail transverse sectional view 40 on line 5—5 Fig. 1.

The spindle bearing illustrated in the accompanying drawings comprises the usual bolster casing 1 having a head flange 2 adapted to be seated upon the spindle rail with a screw threaded portion 3 to receive a nut 45 by which the bolster casing may be clamped to the spindle rail. The head flange 2 is provided with a lateral upwardly extending arm or stand 4 providing an oil reservoir and having a duct 5 leading to the chamber of the 50 bolster casing. The reservoir 4 is provided

with a hinged cover 6 having a projection 7 forming a detent extending over the whorl of the spindle and locking the same against accidental displacement. The bolster casing is provided with a longitudinally extending bore 8 to receive the bolster and the 55 spindle which is mounted therein.

The bolster 9 is of cylindrical form and is provided near its lower end with a narrow enlarged portion forming a lower bearing 10 of slightly less diameter than the bore of the bolster casing and is also provided with an upper enlarged bearing of narrow width which is located below the position of the 60 whorl of the spindle and at a considerable 65 distance from the upper end of the bolster and bolster casing and is of slightly less diameter than the diameter of the bore of the bolster casing. While the upper bearing may be a single enlargement, it desirably is constructed in two narrow sections 11 and 12 which are spaced apart a short distance to 70 provide an oil chamber 13 in the periphery of the bolster casing. The bearing section 11 is provided with a plurality of grooves 14 75 which extend from the periphery of the bearing to at least the diameter of the body 80 of the bolster. The other upper bearing section 12 likewise is provided with grooves 15 which, for convenience in construction, 85 may be in alignment with the grooves 14 so that both sets of grooves may be milled at the same time. By thus locating the upper bearing for the bolster at a considerable distance below the upper end of the bolster and 90 forming the upper bearing in sections spaced apart, the lateral vibration of the upper end 95 of the bolster caused by an unbalanced bobbin is limited, for the reason that the natural vibration of the bolster takes place about a neutral zone which is approximately within the range of the lower section 12 of the upper bearing, and the latter acts, in effect, as a fulcrum for the vibrating spindle. The upper section 11, by engaging the inner 95 wall of the bolster casing, will therefore limit the amplitude of swinging movement of the upper end of the bolster, so that said upper end will not contact with the inner 100 wall of the bolster casing.

wall of the bolster casing and thereby throw oil, as in usual previous constructions.

The body of the bolster above the bearing 11 is of considerably smaller diameter than the diameter of the bearing 11 which is but slightly less than the diameter of the bore. The clearance space 16 thus formed within the bolster casing above the bearing member 11 is relatively long and of considerable capacity, sufficient to retain the oil delivered to it by the pumping action of the vibrating bolster and as the area of the bearing section 11 is relatively small as compared with the internal area of the bolster casing above the bearing section 11, the pumping effect, caused by the lateral movement of the upper end of the bolster as limited by the bearing section 11, is relatively small and insufficient to fill the clearance space 16 and force the oil over the top of the bolster casing. This pumping action is also decreased by reason of the longitudinal grooves 14 of the bearing. Likewise the chamber 13, intermediate of the upper and lower sections 11 and 12 of the upper bearing forms, in effect, a trap which prevents the bearing section 12 from producing an effective pumping action upon the oil into the upper portion of the bolster casing and this is particularly true where, as in the present construction, vertical grooves 15 are also provided in the bearing section 12 to permit the oil to flow down into the lower portion of the bolster casing.

Desirably the bearing sections 11 and 12 are so located upon the bolster that the chamber 13, intermediate of such bearing sections, communicates with the duct 5 leading from the reservoir to the bolster casing so that the fresh oil, which is introduced into the reservoir, will enter beneath the bearing section 11 and above the bearing section 12 and the circulation of the oil from the reservoir will be more or less restricted by the bearing sections 11 and 12. Furthermore by this construction the reservoir, and the duct leading therefrom to the casing, provides a relief for oil which may be more or less entrapped between the bearing sections 11 and 12.

Desirably the portion 17 of the bolster below the bearing 12 is of somewhat smaller diameter than the upper portion of the bolster casing, thereby providing an enlarged oil chamber 18 between the bearing section 12 and the lower bearing 10. The lower end 19 of the bolster desirably is still further reduced in diameter and is internally screw threaded to receive the screw threaded end 20 of a post 21 of the step bearing. The screw threaded portion 20 of the step bearing desirably is connected to the bolster by threads having sufficient clearance to permit a limited vibration of the lower end of the bolster. This screw threaded connection also provides an adjustment by means of which the step

bearing for the lower end of the spindle blade may be adjusted vertically to compensate for the wear of the spindle bearing, or for the accumulation of dirt in the lower end of the spindle bearing. The post 21 of the step for the spindle blade desirably is secured rigidly at its lower end in a cylindrical base 22 having a vertical slot 23 to receive a pin 24 seated in the lower end portion of the bolster casing and which acts to prevent rotation of the base 22. A helical spring 25, which surrounds the post 21 and is provided with an offset lower end 26 which is seated in a groove in the base 22, and which is provided with a similar offset upper end 27 adapted to be seated in one of several grooves 28 in the lower bearing 10 of the bolster, permits a limited yielding rotative movement of the bolster casing in the direction of rotation of the spindle in addition to the usual rocking movement which is permitted in step bearings of this type. Such rotative movement of the bolster in co-operation with the loose screw-threaded connection between the step bearing and the bolster provides the usual automatic vertical adjustment to compensate for the wear of the spindle bearing and the accumulation of dirt in the bearing for the tapered spindle.

The bolster is provided with a longitudinal, tapered bearing 29 which fits the tapered lower end 30 of the spindle blade. The spindle blade has secured to or made integral with it a usual collar 31 having a depending portion provided with a whorl 32 which is located well below the upper end of the bolster casing and beneath the latch 7. The spindle blade also desirably is provided with a downwardly inclined collar 33 which serves to project the oil which rises along the bearing between the tapered portion of the spindle blade and its bearing into the chamber 16 in the upper portion of the bolster casing. The bolster is provided with a plurality of apertures to permit oil to flow from the chambers of the bolster casing into the bearing between the spindle blade and the bolster. One of these apertures 34 is located near the lower bearing. Another aperture 35 desirably is located in the wall of the bolster between the upper and lower sections 11 and 12 of the upper bearing and a third aperture 36 desirably is located a short distance from the upper end of the bolster.

In the operation of the device the self adjustment or self centering of the spindle is readily permitted by reason of the fact that the upper bearing or bearing sections are located at such substantial distance below the upper end of the bolster that the lower section 12 thereof provides a sort of a fulcrum intermediate of the length of the bolster so that the movement of the lower end of the bolster, when the spindle is running under unbalanced load, will readily permit the spindle

to assume its proper position of rotation. By reason of the fact that considerable clearance spaces, which are filled with oil, are located both above and below the upper bearing, the 5 oil will have an advantageous cushioning effect upon the movement of the bolster which will also aid in quickly centering the spindle. The effective surface of the relatively narrow upper bearing sections 11 and 12, is relatively 10 small so that the pumping effect produced by the vibration of the bolster is reduced to a minimum and this effect is still further reduced where the bearing is made in sections, as illustrated, with the considerable space 15 therebetween which communicates with the duct leading to the reservoir. By virtue of this construction the pumping effect due to the vibration of the bolster is practically eliminated.

20 The grooves 14 and 15 in the bearing sections 11 and 12 permit the oil in the clearance space above the bearing section 11 readily to flow downwardly into the lower portion of the bolster casing. Any oil which may be 25 carried up between the tapered spindle blade and its bearing will either be discharged into the upper clearance space 16 through the aperture 36 in the bolster 9, or if carried to the top of the bolster will be deflected downwardly into the clearance space 16 by the ring 33 upon the spindle.

It will be understood that the embodiment 30 of the invention particularly disclosed herein is of an illustrative character and is not 35 restrictive and that various changes in form, construction and arrangement of parts may be made within the spirit and scope of the following claims.

Having thus described the invention, what 40 is claimed as new, and desired to be secured by Letters Patent, is:

1. A self-adjusting spindle bearing construction comprising an oil-containing bolster casing having a cylindrical bore, a bolster therein having a bearing for a spindle blade and provided with external enlarged upper and lower bearings of slightly less diameter than the bore of the bolster casing, a 45 step bearing at the lower end of the bolster 50 adapted to permit a limited vibration thereof, said upper bearing comprising sections of narrow width spaced apart to form a chamber therebetween with the lower section of said upper bearing providing in effect a fulcrum at the neutral zone of normal vibration of the spindle, and the upper section thereof located such distance below the upper end of the bolster and bolster casing that the narrow width of the upper bearing relatively to that 55 of the chambers for the oil above said upper bearing and between the upper and lower sections thereof will avoid pumping of the oil by the vibration of the bolster over the top 60 of the bolster casing.

65 2. A self-adjusting spindle bearing con-

struction comprising an oil-containing bolster casing having a cylindrical bore, a bolster therein having a bearing for a spindle blade and provided with external enlarged upper and lower bearings of slightly less diameter than the bore of the bolster casing, 70 said upper bearing comprising sections of narrow width spaced apart to provide a trap for the oil therebetween, with the lower section of said upper bearing providing in effect a fulcrum located at the neutral zone of normal vibration of the spindle, and the upper section thereof located at such distance below the upper end of the bolster casing as to provide a sufficient clearance spaced above the upper bearing section to prevent pumping of the oil over the top of the casing by the vibration of the bolster, an oil reservoir, and a conduit for conducting the oil from said reservoir into the bolster casing between the upper and lower sections of the upper bearing, thereby providing a relief for the oil trapped therebetween.

3. A self-adjusting spindle bearing construction comprising an oil-containing bolster casing having a cylindrical bore, a bolster therein having a tapered bearing for a spindle blade and provided with upper and lower bearings of slightly less diameter than that of the bore of the bolster casing, an adjustable step bearing for the lower end of the spindle blade comprising a post extending into the barrel of the bolster and having a loose screw threaded connection therewith adapted to permit a limited vibration of said bolster, a base fixedly secured to the lower end of the bolster casing, a helical spring surrounding said post fixedly secured at its respective ends to said base and to said lower bearing operable to permit a limited rotative movement of said bolster, 90 said upper bearing comprising sections of narrow width spaced apart to form a chamber therebetween, with the lower section of said upper bearing providing in effect a fulcrum located at the neutral zone of normal vibration of the spindle, and the upper section thereof located such distance below the upper end of the bolster and bolster casing that the narrow width of the upper bearing relatively to the chambers for the oil above said upper bearing and between the upper section and lower section thereof will avoid pumping of the oil by the vibration of the bolster over the top of the bolster casing, a reservoir, a conduit leading from the reservoir to the chamber between the upper and lower sections of the upper bearing, and an aperture in the wall of said bolster between the upper and lower sections of the upper bearing communicating with the bearing for the spindle blade.

In testimony whereof, I have signed my name to this specification.

JOSEPH A. MILLER.
